CLAIM

The ornamental design for a radiator support cover for a vehicle as shown and described.

DESCRIPTION

FIG. 1 is a front perspective view of a radiator support cover for a vehicle embodying our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front perspective view thereof when connected to an exemplary vehicle radiator.

The broken line showing of the vehicle radiator is provided for the purposes of illustrating environmental structure and forms no part of the claimed design.

1 Claim, 8 Drawing Sheets
